UNITED STATES PATENT OFFICE.

FREDERICK WM. HILL, OF BOSTON, MASSACHUSETTS.

ROLLER-SKATE.

1,216,690.

Specification of Letters Patent. Patented Feb. 20, 1917.

Application filed June 21, 1916. Serial No. 105,034.

To all whom it may concern:

Be it known that I, FREDERICK WM. HILL, a citizen of the United States, and a resident of Boston, county of Suffolk, and State 5 of Massachusetts, have invented an Improvement in Roller-Skates, of which the following description, in connection with the accompanying drawings, is a specification, like characters on the drawings representing 10 like parts.

My invention relates to roller skates and in the illustrative embodiment herein described I have shown a skate adapted for attachment to one foot of the wearer and 15 provided with propelling means that can be operated by the wearer's other foot.

In the drawings:

Figure 1 is a plan view of one illustrative embodiment of my invention; 20 Fig. 2 is a side elevation of the same; Figs. 3, 4 and 5 show modifications; and Fig. 6 shows a plan view of Fig. 5. A foot rest of any ordinary type is shown at 1, provided with the usual clamps 2 for 25 securing the skate to the shoe. The foot rest 1 is mounted at the front upon a suitable wheel or wheels 3 and upon the driving wheel 4 at the rear. The driving wheel 4 is journaled in any usual manner as in the 30 brackets 5 attached to the foot rest and is provided with the usual clamps 2 for 35 securing the skate to the shoe. The foot rest 1 is mounted at the front upon a suitable wheel or wheels 3 and upon the driving wheel 4 at the rear. The driving wheel 4 is journaled in any usual manner as in the brackets 5 attached to the foot rest and is provided with the usual clamps 2 for 40 securing the skate to the shoe. The foot rest 1 is mounted at the front upon a suitable wheel or wheels 3 and upon the driving wheel 4 at the rear. The driving wheel 4 is journaled in any usual manner as in the brackets 5 attached to the foot rest and is provided with the usual clamps 2 for 45 securing the skate to the shoe. The foot rest 1 is mounted at the front upon a suitable wheel or wheels 3 and upon the driving wheel 4 at the rear. The driving wheel 4 is journaled in any usual manner as in the brackets 5 attached to the foot rest and is provided with the usual clamps 2 for 50 securing the skate to the shoe.

Mounted upon the foot rest 1 is the fulcrum support 8 upon which is fulcrumed the foot lever 7 to one end of which is attached the strap or thong 9 which winds upon the drum 6. The lever 7 may be provided at its 55 other end with a foot pedal 10.

In operation the pedal 10 may serve not only as a convenient surface against which the driving foot thrusts in propelling the skate but may also serve as a rest for the 55 driving foot when the wearer desires to coast

or to run along under the momentum obtained by previous strokes.

The foot pedal 10 is shown pivoted to the lever 7 at 11, the lever 7 having two ears 12 and 13 which support the pedal 10 either in its outer position as shown in full line, or in its inner position as shown in dotted lines.

By turning the pedal 10 on its pivot 11 from one position to the other, the leverage may be changed to vary the speed or power 65 with which the skate may be driven. Going up grade it would be desirable to have strong leverage and the user would have the pedal 10 in its outer position. On the level, where less power would be needed, the inner position of the pedal might be more 70 convenient.

In Figs. 3, 4 and 5 I have shown modifications of means for mounting the driving lever 7 together with means for changing the leverage. 75

In Fig. 3 I have shown the lever 7 mounted upon an irregularly shaped cam 14 provided with flanges 15 to keep the lever 7 from slipping off the cam. In the flange 15 may be cut a slot 16 which may be engaged by a pin 17 attached to the lever 7, to keep the lever from sliding lengthwise. Using this modification, high leverage for climbing grades may be attained 80 by pushing the lever 7 up and down with short strokes, fulcruming the lever on the rearward portion of the cam,—while greater speed at the expense of power, can be obtained by pushing the lever farther down, 85 making it fulcrum near the forward surface of the cam, farther from the driving wheel 4.

In Fig. 4 I have shown a semi-circular cam 18 attached to the under side of the lever 7, the cam 18 being adapted to rock upon the foot rest 1 between two wings 19 mounted thereon. With such an arrangement as this there will be a constant change 90 of leverage during each part of the stroke of the lever 7.

In Fig. 5 I have shown a similar modification but have mounted the semi-circular cam 18 upon the foot rest 1 of the skate and have provided the cam with cogs which 95 engage a toothed rack 20 on the under side of the lever 7.

In using my invention many of the disadvantages inherent in other power roller skates are obviated. It is possible for the 110

wearer of my skate to stand still, walk upstairs, etc., with the skate on his foot without the inconvenience experienced in using other skates whereby the mere weight or 5 inclination of the foot of the wearer drives the skate.

It is obvious that many modifications or variations of my invention might be made without departing from the scope or spirit 10 thereof and I do not wish to be limited to the specific type or types of roller skate shown and described.

Having described my invention, I claim:

1. A power skate comprising in combination 15 foot-supporting means, and skate-driving means whereby the skate may be driven by application of power through the other foot.

2. A power skate comprising foot-supporting means resting upon wheels and 20 driving means for positively rotating one or more of said wheels and including a lever adapted to be operated by the other foot of the wearer.

Copies of this patent may be obtained for five cents each, by addressing the "Commissioner of Patents, Washington, D. C."

3. A power skate comprising foot-supporting means and skate-driving mechanism provided with means for changing the purchase or power leverage with which the driving mechanism is operated.

4. In a power skate, foot-supporting means, skate-driving means including a jointed lever constructed to permit the user to change the distance between the point at which the power is applied and the fulcrum of the lever.

5. A power skate comprising in combination the foot rest 1, the driving wheel 4, the lever 7 connected thereto and fulcrumed on said foot support whereby the skate may be driven by the up-and-down motion of 40 the lever 7.

In testimony whereof, I have signed my name to this specification, in the presence of two subscribing witnesses.

FREDERICK WM. HILL.
